CASE FOR CARRYING AND STORING DETONATORS OR SIMILAR ARTICLE

William Harry Donkin, London, England, assignor to Godfrey Holmes (Plastics) Limited, Lincoln, England,
a British company

Application October 22, 1954, Serial No. 32,792

Term of patent 14 years

(Cl. D58—13)

Fig. 1.

Fig. 2.

Fig. 3.

Fig. 1 is a perspective view from above and one side of a case for carrying and storing detonators or similar articles showing my new design;

Fig. 2 is a top plan view thereof; and

Fig. 3 is a perspective view showing the bottom and opposite side thereof.

I claim:

The ornamental design for a case for carrying and storing detonators or similar article, substantially as shown.
